(57) **CLAIM**

The ornamental design for a two-toned teakettle body, as shown and described.

DESCRIPTION

FIG. 1 is a side, top perspective view of a two-toned teakettle body showing our new design;

FIG. 2 is a top view thereof;

FIG. 3 is a front view thereof;

FIG. 4 is a left side view thereof; and,

FIG. 5 is a rear view thereof.

The broken lines in the drawing are for illustrative purposes only and form no part of the claimed design.
